MARK R. BRINEY, OF BROOKHAVEN, NEW YORK

CAR-ACTUATED CIRCUIT CONTROLLER FOR CROSSING SIGNALS

Application filed December 25, 1930. Serial No. 504,658.

This invention relates to a car-actuated circuit controller adapted to be used more particularly in the operation of railway-crossing signals of the alternate flash type, and involves the use of similar but reversely arranged track instruments located at more or less remote distances from, and at opposite ends of, the crossing, each of which is provided with car-operating means for causing the operation of the signal while moving therefrom in one direction toward the crossing, but is rendered ineffective when the car or train has passed the crossing beyond the other instrument, and one of the objects of the present invention is to provide an additional or intermediate track instrument having car-actuated means for causing the continued operation of the signal while the car or train is passing the crossing in either direction.

20 In other words the main object of the present invention is to provide simple and efficient car-actuated means for initiating the operation of the signal while the train is passing in one direction and for maintaining such operation until the train has passed the intermediate or crossing instrument, and at the same time to render the operation of the other first-named instrument ineffective upon the signal as the train continues to move 30 in the same direction.

Other objects and uses relating to specific parts of the apparatus will be brought out in the following description.

The drawing shows diagrammatically a 35 railway crossing signal-operating system embodying the various features of my invention, portions of one of the rails of the track with which the several instruments are associated being broken away.

40 In order that the invention may be clearly understood I have shown one of the rails —1— of a railway track as extending across a highway crossing zone indicated at —A—, and additional approaching zones —B— and —C— located along the railway at more or less remote distances from the crossing zone —A—.

45 A track instrument —A'— is located with- 50 in the crossing zone —A— adjacent the rail

—1— to be operated by a car or train in a manner hereinafter described.

A pair of similar but reversely arranged track instruments —B'— and —C'— are located respectively within the zones —B— 55 and —C— adjacent the track —1— to be operated by the passing car in a manner hereinafter more particularly described.

The track instrument —B'— comprises separate car-operated members —2— and —3— arranged in sequence toward the crossing and preferably closely adjacent the inner side of the rail —1— for transverse movement between the rails of the track, the ends of both members being deflected inwardly 60 to enable the flange of the car wheel as —4— to roll between the inner face of the ball of the rail and members —2— and —3—, for sequentially moving said members inwardly 65 as the train travels through the zone —B— to the crossing zone —A—, said members —2— and —3— being automatically returned to their normal positions by springs —5— after the car or train has passed beyond both 70 members.

75 The member —2— is operatively connected to a movable switch terminal —6— of a normally open electric switch —7— having its other terminal —8— mechanically connected to the member —3— through the medium of a leverage system —9— and connecting rod —9'— arranged in such manner that the inward movement of the member —3— will withdraw the switch terminal —8— out of contact with its companion terminal —6— 80 for a purpose hereinafter more fully described.

85 The contact terminals —6— and —8— are electrically connected in the battery circuit —10—, deriving current from a battery 90 —11— or other source of electric current supply.

95 The switch —7— is normally open but immediately upon the inward movement of the member —2— by engagement of the car wheels —4— therewith as the train is moving toward the crossing, the switch terminal —6— will be moved into contact with the switch terminal —8— to close the circuit 100 —10— which comprises battery 11, wire 10',

terminals 8 and 6, wire 10, relay 13 and wire 10, but immediately following this operation the track member —3— will be forced inwardly by the same car-wheels, thereby operating the leverage system —9— to withdraw the terminal —8— from contact with the terminal —6— for breaking the circuit which continues broken until the car or train has passed beyond the track member —3— 10 toward the crossing.

Suitable devices such as dash-pots —12'— and —12— have their respective pistons operatively connected to the corresponding track members —2— and —3— to retard the closing movements of said members by their respective springs —5—, also for a purpose hereinafter described.

The relay included in circuit 10 is energized by the closing of the switch —7— for 20 closing a normally open electric switch —14— of a branch circuit —15— comprising battery 11, wires 10' and 15, switch 14, wire 15', switch 36, wires 15'' and 10, relay 13 and wire 10 so as to continue the energizing of the relay 25 —13— and resultant maintaining of the switch —14— in the closed position independently of the track instrument —B'— or until the car or train reaches and engages the track instrument —A'— at the crossing zone —A— 30 at which time said switch 14 will return to the open position due to the relay 13 becoming de-energized by the opening of the switch 36 as will hereinafter be more fully described.

A second normally open electric switch 35 —16— actuated by the relay 13 and connected with wire 15 is electrically connected in another branch circuit —18— including therein a vibrating relay —19— and a make and break electric switch —20— that is connected with 40 the negative side of the battery 11 by wires 18' and 10'' and which has a self-closing movable member —21— pivoted at —22— and adapted to be opened by self-retracting armature —23— of the relay —19—.

45 The armature —23— is arranged to engage and open the switch member —21— instantly upon the energization of the relay —19—, thereby breaking the circuit through the relay for de-energizing the same and allowing the armature —23— and switch member —21— to return to their normal positions for re-energizing the relay to repeat the operation, resulting in a more or less regular vibration of the armature, one end of which 50 is weighted by a pair of radially spaced posts —24—.

These posts serve as counterweights for 55 returning the armature —23— to its open position and also for operating a vibratory switch member —25— of an electric switch —26— having a pair of terminals —27— adapted to be alternately engaged by the switch member —25— as the latter is oscillated in reverse directions by engagement

with the posts —24— during the closing movements of the armature.

The double pole switch —26— is electrically connected with the wire 18 and in a branch circuit —28— including therein an electric signal consisting, in this instance, of a pair of flash lamps —29— which are energized from battery 11 through switch 16, double pole switch 26 and circuit 28.

It is now evident that a car or train passing 75 the track instrument —B'— toward the crossing —A— will cause the oscillation of the armature —23— and switch member —25— and resultant alternate flash of the signals —29—, it being understood that the switch members —14— and —16— will remain closed until the train reaches and operates the track instrument —A'— at the crossing —A—, at which time the relay circuit —15— will be opened in a manner presently described, thereby de-energizing the relay 80 —13— and permitting the switches —14— and —16— to open.

It is desirable, however, to maintain the automatic operation of the signals —29— 85 while the car or train is passing the crossing —A—, and in order that this may be accomplished simultaneously with the breaking of the relay circuit —15— by the opening of switch 36, the track instrument —A'— at the 90 crossing is provided with a car-operated member —30— somewhat similar to the members —2— and —3— in that it is normally spring-pressed against the rail by springs —31—, and is adapted to be opened against 95 the action of the springs by the flange of the car wheel.

The member —30— is connected by a link 100 —32— to one end of a lever —33— carrying at its other end movable switch members —34— and —35— of corresponding electric switches —36— and —37—, the other members —38— and —39— of the switches —36— and —37— being relatively fixed so that 105 when the track member —30— is forced inwardly by the car wheels against the action of the springs —31— it will open both of the switches —36— and —37—.

It is now evident that the opening of the switch —36— will break the circuit —15— 110 and thereby de-energize the relay —13— to allow the opening of the electric switches —14— and —16—.

The other switch —37— is connected in a branch circuit —40— including therein an electric switch —41— electrically connected with wire 15 and having its movable member connected by the link —17— to the movable switch members of the electric switches —14— and —16— for simultaneous movement therewith so that when the switches —14— and —16— are opened the remaining switch —41— will be closed.

115 It will now be remembered that after the relay —13— has been once energized by the 120

closing of the switch —7— it will remain energized although switch 7 returns to its open position by current passing from battery 11 through wires 10' and 15, switch 14, line 15', switch 36 and line 15'', and thence through the relay 13 and back to the battery through line 10'' for maintaining the switches —14— and —16— closed and opening the switch —41— until the car or train actually engages and operates the member —30— at the crossing —A—, but immediately upon the operation of the member —30— from its normal position the relay —13— will be de-energized by the opening of switch 36 to allow the switches —14— and —16— to open and the switch —41— to close.

Suitable mechanism is provided for causing a continued operation of the signals —29— while the car or train is passing the crossing. For this latter purpose an electric switch —42— is connected in a branch circuit —43— which includes therein the vibratory relay —19—, previously described, as the means for causing the oscillation of the switch member —25— into alternate contact with the terminals —27— of the signal circuit —28— for alternately energizing the flash signals —29—, it being understood that the switch —42— will then be closed in a manner presently described.

Associated with the electric switch —42— is a similar electric switch —44— which is connected in a branch circuit —45— including therein a vibratory relay —46— and an electric switch —47— controlled thereby.

That is, the relay —46— is provided with an armature —48— similar to the armature —23— in that it is provided with counter-balancing posts —49— for operating an oscillatory switch member —50— of an electric switch —51— having opposed contact terminals —52— to be alternately engaged by the oscillating member —50—.

This electric switch —51— is connected in another branch circuit —53— including therein cooperative relays —54— and —55— and an electric switch —56—, said relays —54— and —55— and electric switch —56— being connected in series and in sequence in the branch circuit —53—.

Attention is here called to the fact that when no car or train approaches the crossing the electric switches —7—, —14— and —16— will be normally open while the electric switches —36—, —37— and —41— will be normally closed but, as previously explained, the electric switch —56— has its movable member secured to the armature —57— of the relay —55— which is energized from battery 11, through wires 10' and 15, switch 41, wire 40, switch 37, wires 40' and 53', and thence through relay 55, wire 53'' and switch 56 to wire 28 as long as the electric switches —37— and —41— remain closed, or when no car or train approaches the crossing, thereby

normally maintaining the switch —56— closed against the action of the retracting spring —58—.

A normally open self-opening electric switch —59— is connected in parallel with the switch —56— to be controlled in a manner presently described, it being understood that the electric switches —42— and —44— are of the self-closing type.

The means for controlling the electric switches —42—, —44— and —59— comprises, in this instance, a ratchet wheel —60— carrying at one side of its axis a weighted arm —61— which tends to rotate the ratchet wheel in a counter-clockwise direction, said arm —61— being provided with shoulders —62— and —63— adapted to simultaneously engage and open the movable members of the switches —42— and —44— when the ratchet wheel is rotated in a clockwise direction as indicated by arrow —x—, the arm —61— being also provided with a shoulder —64— adapted to engage and close the switch —59— when the ratchet wheel is released for allowing the switches —42— and —44— to close.

The rotation of the ratchet wheel —60— and its arm —61— in a clockwise direction is limited by means of a stop —65— engaging said arm immediately following the opening of the switches —42— and —44—.

The means for rotating the ratchet wheel —60— in a clockwise direction against the action of the counterweighted arm —61— comprises a pawl —66— which is pivotally mounted at —67— upon an armature lever —68— which is pivotally supported at —69— and is adapted to be operated against the action of retracting spring —70— by the intermittent energizing of the relay —54— in a manner presently described.

Suitable stop pawl —71— is pivotally supported at —72— and is yieldingly held in engagement with the teeth of the ratchet wheel by spring —73—.

The pawls —66— and —71— are preferably of the bell-crank type having respective arms —74— and —75— projecting toward each other in the path of the U-shaped arm —76— of the armature —57— which latter is also of the bell-crank type and is pivotally supported at —57'—.

It is now clear that as long as no train approaches the crossing and with the switch 59 maintained in the closed position by the arm 61 being in its lowermost position the resultant closed position of the switch 37 will cause the relay 55 to remain energized by current from the battery 11 passing through wires 10' and 15, switch 41, wire 40, switch 37, wires 40' and 53', relay 55, wire 53'', and through switch 56 or switch 59 to line 28 and thereby hold the pawl-controlling member —76— of the armature —57— out of contact with the adjacent arms —74— and —75—.

of the pawls —66— and —71— against the action of the spring —58—, under which conditions the switch —47— will be intermittently opened and closed by the vibratory operation of the armature —48— due to the intermittently energizing of relay 46 by current passing from the battery 11 through wire 43, the closed switch 44, wire 45 and through relay 43, switch 47 and wires 45' and 28 to the battery, thereby causing the oscillation of the switch member —50— to produce a corresponding intermittent energizing of the relay 54 by current passing from wire 45 through wire 45'', switch 52, wire 53, and thence through relay 54 to wire 53' and resultant oscillation of the armature —68— which causes the pawl —66— to move backward and forward for rotating the ratchet wheel —60— and its counterweighted arm —61— in a clockwise direction until limited by the engagement of said arm with the stop —65—, at which time the switches —42— and —44— will have been opened by said arm.

It will be noted, however, that immediately upon the entrance of the car or train into the zone —B— toward the crossing zone —A— the inward depression of the track member —2— by the car wheel will close the electric switch —7— thus closing the circuit from the battery 11, passing through line 10', switch 7 and line 10 to relay 13, and thence through wire 10'' to the battery, thereby energizing the relay —13— for closing the switches —14— and —16— and thereby starting the operation of the flash signals —29— in the manner previously described, and that immediately following the displacement of the track member —2— the track member —3— will be operated by the same car or train to open the switch —7—, but before that takes place the closing of the switch —14— will have closed the circuit through lines 15 and 15', switch 36, line 15'' and through relay 13, and line 10 to battery 11 for maintaining relay 13 energized and the continued operation of the signals until the car or train displaces the track member —30— at the crossing —A—, at which time the switch member —36— will have been opened, thereby breaking the circuit through the relay —13— and allowing the switches —14— and —16— to open and the switch —41— to close.

It will be observed, however, that at this time the switch member —37— will have been opened, thereby opening the circuit passing from battery 11 through wires 10' and 15, switch 41, wire 40, switch 37 and lines 40' and 53' through relay 55, wire 53 and switch 56 to wire 28 and back to the battery thus de-energizing the relay —55— which allows the spring —58— to retract the armature —57— and its pawl-operating member —76— to engage and trip both of the pawls —66— and —71— out of contact with the

teeth of the ratchet wheel —60— and permitting the weighted arm —61— to rotate the ratchet wheel in a counter-clockwise direction until the shoulder —64— on the arm —61— engages and closes the switch —59—, and at the same time permitting the electrical switches —42— and —44— to close.

This operation of the armature —57— by its retracting spring —58— opens the switch —56— simultaneously with the tripping of the pawls —66— and —71—.

It will now be remembered that while the train is passing the crossing zone —A— both of the switches —36— and —37— will be opened by the continued operation of the track member —30—.

This closing of the switch —42— immediately cuts in the relay —19— in the battery circuit passing through line 43, switch 42, wire 43' and through relay 19 and switch 20 to battery through lines 18' and 10, thereby continuing the vibratory operation of the armature —23— by reason of its alternate opening and closing of the corresponding switch —20—, thereby effecting the continued oscillation of the switch member —25— and resultant continued operation of the flash signals —29— during the passing of the train through zone —A— in the manner previously explained.

The electrical switch —44— being now closed by the recession of the weighted arm —61— therefrom, the switch —59— will be closed by the contact of said weighted arm therewith, thus permitting the battery current to flow through the wire 43, switch 44, wire 45 and relay —46— and intermittently through the switch —47— and wires 45' and 28 to battery 11, which causes a corresponding vibration or impulsive movement of the switch member —50— into alternate contact with the terminals —52— of the circuit passing from line 45 through wire 45'', switch 51 and line —53— in which the relay —54— is connected, thereby causing an intermittent operation of the pawl —66— and corresponding rotation of the ratchet wheel —60— and its weighted arm —61— into and out of engagement with the movable member of the switch —59—.

Owing to the fact that the relay —55— is electrically connected in series with the relay —54—, the resultant energizing of the relay —55— will also be impulsive, either through the closing of the switch —56— by the armature —57—, or by the closing of the switch —59— through the engagement of the weighted arm —61— therewith.

It is now clear that as long as the car or train continues to pass through the crossing zone —A— the switches —36— and —37— will remain open, the effect of which is to de-energize the relay —55— and allow the armature —57— to be actuated by the

spring —58— to open the switch —56— and simultaneously trip the pawls —66— and —71— from their holding positions, thus allowing the weighted member —61— and ratchet wheel —60— to revolve in a counter-clockwise direction to allow the switches —42— and —44— to close and to cause the closing of the switch —59—.

This closing of the switch —59— closes the circuit passing from battery 11 through line 43, switch 44, lines 45 and 45'', through switch 51, line 53 and relay 54, thence to the battery through line 53', relay 55, switch 59 and line 28 and causes the energizing of the relay —55— to withdraw the member —76— out of engagement with the pawls —66— and —71— so that the pulsatory current operating through the relay —54— will cause the pawl —66— to engage and rotate the ratchet wheel —60— and its weighted member —61— clockwise, thereby allowing the switches —59— and —56— to again open, thus permitting the weighted arm —61— to again close the switch —59— to energize the relay —55— to close the switch —56—, these operations being repeated at frequent intervals as long as the train is passing the crossing zone —A—, during which the signals —29— will continue to operate in a manner described.

As soon as the car or train has passed the track member —30— the latter will be slowly returned to its normal position, thereby causing the switches —36— and —37— to return to their normal closed or starting positions.

At this time the switches —42— and —44— will still be closed, thereby continuing the energizing of the relay —19— and resultant operation of the signals —29— for a limited period of time or until the ratchet wheel —60— and its weighted arm —61— have been returned to their starting positions for opening the switches —42— and —44—.

Immediately upon the closing of the switch —37— the relay —55— will be energized by circuit passing from battery 11 through lines 10' and 15, switch 41, line 40, switch 37 and lines 40' and 53' through relay 55, and thence to the battery through switch 59 and lines 50 and 28 to actuate the armature 57 against the action of spring 58 for closing switch 56, and at the same time to withdraw the member —76— from its pawl-engaging position and allowing the pawls to re-engage the teeth of the ratchet wheel —60—, during which the current flow through the closed switch —44— will energize the relays —46— and —54—, causing a pulsatory action of the pawl —66— for rotating the ratchet wheel —60— and its weighted arm —61— in a clockwise direction in the manner previously described until the weighted member engages and opens the movable members of both of the members —42— and —44—, thereby breaking the circuit through the signal controlling relay

—19— and also breaking the circuit through the relays —46— and —54—, while the relay —55— still remains energized due to the current passing through the now closed switch 56 to hold the member, —76— out of engagement with the pawls —66— and —71—, thereby permitting the pawls to hold the ratchet wheel in its starting position with its weighted member —61— opening both of the switches —42— and —44—, thus completing the cycle of operation.

As previously stated the zone —C— at the other end of the crossing zone is equipped with a track instrument similar to that shown at station —B— except that its car-operated members as —2'— and —3'— are arranged in a reverse order so that a car or train passing from zone —B— through the crossing zone —A— and beyond the station —C— will first effect the operation of the member —3'— to withdraw the switch member —8— from its companion switch member —6— for further opening the switch as —7'—, and thus preventing the closing of switch 7' as the train engages member 2' and the operation of the signals —29— while the train continues in that direction through zone —C—.

On the other hand, a train approaching the zone —C— from the opposite direction toward the crossing —A— will first operate the member —2'— to close the switch 7' whereupon the relay 13 will be energized by current passing from battery 11 through wire 81, switch 7' and wires 82 and 10 to relay 13, and thence back to the battery through line 10'' and immediately following this operation the train will engage and operate the member —3'— to withdraw the switch member —8'— away from its companion switch member —6'— to open the switch 7' and effect the operation of the signals 29 in substantially the same manner as previously described for the track instrument —B'—. As the train continues to move from the zone —C— into the crossing zone —A— the track member —30— of the instrument —A'— will be opened in the manner previously described to maintain the continued operation of the signals —29— in the same manner as described for a train moving from station —E— to station —A—.

It will be noted, however, that as the train continues to move from station —C— through station —A— and onward to station —B— it will first operate the member —3— to withdraw the switch member —8— out of the range of movement of the switch member —6— when the latter is operated by the inward movement of the track member —2—.

Under these conditions it is evident that the signals will be operated by a car or train moving along the track in either direction until it has passed the track instrument at

the crossing and that the track instrument at either end of the crossing will be operated by a train moving from that instrument toward and beyond the crossing without effecting the operation of the other track instrument, thus producing what may be called a directional car-controlled signal.

The construction and operation of the apparatus has been described in such full, clear and exact terms as to enable anyone skilled in the art to make and use the same, but it is obvious that various changes may be made in the detail construction without departing from the spirit of this invention.

15 What I claim is:—

1. In a car-actuated circuit controller for railways, an electric circuit including therein a normally open electric switch, car-operated members arranged in sequence along the railway in the direction of movement of the car, means actuated by the first-member for closing the switch, and means actuated by the second member for opening the switch and holding it open until the car passes the second member, and means for maintaining the switch open and restoring said members after the car passes the second member.

2. In a car-actuated circuit controller for railways, an electric circuit including therein a normally open electric switch, car-operated members arranged in sequence along the railway in the direction of movement of the car, means actuated by the first-member for closing the switch, and means actuated by the second member for opening the switch and holding it open until the car passes the second member, and means for restoring said members after the car passes the second member, an electric signal distant from said members in the direction of movement of the car, and means brought into action by the closing of the switch for operating said signal, and for continuing said operation after the switch is opened by the second member.

3. In a single-direction car-actuated circuit controller for railways, a track instrument comprising a normally open self-opening electric switch in the circuit to be controlled, car-operated members arranged in juxtaposed sequence adjacent the track, means actuated by the first member for closing the switch, and means actuated by the second member for opening the switch and for holding it open until the car has passed the same, a second track instrument distant from the first-named track instrument in the direction of movement of the car, and provided with a normally closed electric switch and a car-actuated member for opening the switch, means brought into action by the closing of the first-named switch for causing the operation of the signal and for continuing said operation while the car is passing from the first-named instrument to the second instru-

ment, and means brought into action by the opening of the switch of the second instrument for continuing the operation of the signal independently of the first-named instrument while the car is passing the second instrument.

4. In a single-direction car-actuated circuit controller for railways, a track instrument comprising a normally open self-opening electric switch in the circuit to be controlled, car-operated members arranged in juxtaposed sequence adjacent the track, means actuated by the first member for closing the switch, and means actuated by the second member for opening the switch and for holding it open until the car has passed the same, a second track instrument distant from the first-named track instrument in the direction of movement of the car, and provided with a normally closed electric switch and a car-actuated member for opening the switch, means brought into action by the closing of the first-named switch for causing the operation of the signal and for continuing said operation while the car is passing from the first-named instrument to the second instrument, and means brought into action by the opening of the switch of the second instrument for continuing the operation of the signal independently of the first-named instrument while the car is passing the second instrument, said switch of the second-named instrument being adapted to close as soon as the car has passed said second instrument, and means brought into action by the closing of the switch of the second instrument for stopping the further operation of the signals.

In witness whereof I have hereunto set my hand this 15 day of December, 1930.

MARK R. BRINEY.
